UNITED STATES PATENT OFFICE.

HORACE J. YOUNT, OF INDIANAPOLIS, INDIANA.

SCORED-CYLINDER REPAIR.

1,217,546.

Specification of Letters Patent. Patented Feb. 27, 1917.

Application filed May 22, 1916. Serial No. 99,192.

To all whom it may concern:

Be it known that I, HORACE J. YOUNT, a citizen of the United States, residing at Indianapolis, in the county of Marion and State of Indiana, have invented certain new and useful Improvements in Scored-Cylinder Repair, of which the following is a specification.

In internal combustion engines for automobiles, boats and the like, the connecting rods are attached to the pistons by the medium of a piston pin which is secured in an eye at the end of the connecting rod. This pin, from carelessness and other causes, very frequently becomes loose and working endwise by use contacts with the inner wall of the cylinder and wears grooves or scores in it causing leakage past the piston which the packing rings cannot close. This scoring of the interior of the cylinder is often developed on two of its diametrically opposite sides by reason of the loose pin shifting often and contacting with the cylinder at its alternate opposite ends. Automobiles as now constructed each commonly have from four to twelve cylinders which proportionately increases the chances of trouble from scoring, and these cylinders are generally cast in integral groups which would necessitate the discarding of the group to displace a scored cylinder with a new one.

Various expedients have been resorted to for repairing scored cylinders, the one meeting with the most favor being to weld in metal strips to fill the scores; but this involves the heating of the cylinder to so high a temperature that it becomes warped, requiring it to be bored out to a greater than the original diameter. Besides the labor involved this necessitates the discarding of the old piston for a larger one and the changes in size throw this part of the engine out of time with the rest.

The object of my invention is to repair a scored cylinder and make it as good as new without heating it or enlarging its bore, and to accomplish this at such a satisfactory saving in cost over the expense of a new one as will make the repair of scored cylinders always worth while.

Referring to the accompanying drawing which is illustrative of my invention

Figure 1 is a longitudinal central section of a scored cylinder before it has been repaired, and Fig. 2 is a perspective view on a larger scale of a scored cylinder after it

has been repaired in accordance with my invention.

In Fig. 1, the cylinder 3, piston 4, connecting rod 5 attached to the piston by pin 6 (which is generally hollow), shaft 7 and crank 8, are of usual and well known construction, and the piston is shown with a pair of parallel scores 9, formed by the contact of the end of pin 6.

In the exercise of my invention these scores or grooves, if they are not too wide, are individually widened at their inner or bottom portions by the aid of a planing machine or otherwise, to form channels which are dovetail in cross section, or if the surface between the scores is so damaged as to need entire renewal I make a single channel of sufficient width to embrace both score lines, the purpose being always to remove all of the broken and damaged interior surface of the cylinder. In all cases the channel is formed with longitudinal inwardly beveled edges.

In the channel thus formed I fit a strip 80 of metal, preferably copper, which expands more rapidly when heated than does the cast iron from which the cylinder is cast. This metal strip is thicker than the depth of the channel. It is inserted by slipping it in 85 endwise through the outer end of the channel and is made to fit as closely as possible for easy driving insertion. It is then thoroughly expanded by hammering or rolling along its entire exposed surface until every 90 portion of the channel is filled and it is as tight as it can be made in this way. Then the projecting portions of the hammered copper are removed and it is made to conform by careful scraping to the curved surface of the inner bore of the cylinder.

This completes the operation. The pair of narrow parallel copper strips 10 are easier to finish to the interior surface of the cylinder than is the wider strip 10' but in all 100 cases I have found by experience that the repair is perfect in operation and is durable. The copper being inserted and finished cold will additionally tighten when the cylinder becomes heated in use because its expansibility from heat is greater than that of the iron with which it is associated.

I do not desire to be limited to the use of copper, as its alloys as well as other metals will give satisfactory results, nor do I desire to limit my invention to a channel the shape of which is dovetail in cross section, but

what I do claim as new and wish to secure by Letters Patent of the United States, is—

The combination with a reciprocating piston of a cylinder in which the piston reciprocates, said cylinder having channels with undercut sides in its inner wall surface and metal filling said channels, said metal having greater relative expansibility than the

metal of the cylinder, and said metal conforming in outside shape with the bore of the cylinder.

In witness whereof, I have hereunto set my hand and seal at Indianapolis, Indiana, this 12th day of May, A. D. one thousand nine hundred and sixteen.

HORACE J. YOUNT. [L.S.]
